[57] CLAIM

The ornamental design for a video game display, as shown and described.

DESCRIPTION

FIG. 1 is a perspective view of a video game display showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing of a portion of the ceiling in FIGS.

1, 2, 4, 5 & 6 is for illustrative purposes only and forms no part of the claimed design. The pole which extends into such broken lines is of an indeterminate length.
